VERNON MERRITT, OF MONTGOMERY, ALABAMA

ANTIFREEZING APPARATUS

Application filed May 27, 1930. Serial No. 456,096.

My invention relates to anti-freezing apparatus and an object of the same is to provide a mechanism whereby a valve will be automatically closed to prevent the passage of water or other liquid through a pipe line upon the water reaching a freezing temperature.

A further object of the invention is to provide an automatically operated valve which embodies a longitudinally movable plunger which is operated to close the valve incident to formation of ice in a receptacle together with means for melting the ice in such receptacle to permit the plunger to return to normal position and thereby open the valve.

Another object of the invention is to provide a mechanism of this character embodying an electrical heating unit for melting the ice in the receptacle and a switch for controlling a circuit through the heating unit which is automatically closed to complete the circuit after the valve actuating plunger has been moved in a direction to open the valve.

With the preceding and other objects and advantages in mind, the invention consists in the novel combination of elements, constructions and arrangements of parts and operations to be hereinafter more fully described, claimed and illustrated in the accompanying drawings, wherein:

Figure 1 is a top plan view of my invention;

Fig. 2 is a longitudinal sectional view of the same taken on line 2—2 of Fig. 1.

Fig. 3 is a section taken on line 3—3 of Fig. 2;

Fig. 4 is a sectional view taken on line 4—4 of Fig. 2;

Fig. 5 is an enlarged detail view.

Fig. 6 is a perspective of one of the elements embodied in the invention; and

Fig. 7 is a perspective of the valve actuating handle embodied in the invention.

Referring to the invention in detail a receptacle 5 is provided in which a horizontal partition 6 is arranged. The partition 6 divides the receptacle into an upper compartment 7 and a lower compartment 8, the latter having a drain valve 9a.

In order to obviate the bursting of the re-

ceptacle when expansion occurs therein the side walls of the compartment 7 are arranged in divergent relation as indicated at 9. The upper wall of the receptacle is provided with a filling opening 10 which is normally closed by a removable cap 11. A drain cock 7a is provided for the upper compartment so that the liquid can be kept at a predetermined level. Communication between the compartments 7 and 8 is established by way of a rectangular conduit 12 having one end arranged flush with the upper face of the partition 6. The conduit 12 is provided with a tapered bore 13 which decreases towards its upper end so that liquid from the compartment 7 will pass into the compartment 8 and keep the same always full. Due to the shape of the bore 13 ice will first form therein and prevent any liquid passing from the lower to the upper compartment. In this connection it is pointed out that the lower compartment must always be filled with liquid in order that sufficient expansion take place therein to cause the rod 19 to move the requisite distance when the liquid freezes. Thus any leakage from the lower compartment will be compensated for by the liquid in the upper compartment passing therein as above stated.

In order to permit air to pass from the lower compartment when the liquid from the upper compartment flows therein a conduit 12a having a tapered bore 13a is arranged in the forward end of the partition 6 and is of such height as to extend above the normal liquid level of the upper compartment.

The tapered or wedge shape of the bore 13a is for the purpose of forming a wedge shaped block of ice at the beginning of the freezing operation, which will effectually close the passage and prevent the escape of any of the liquid from the lower vessel as the freezing process progresses.

Extending horizontally from the front wall of the compartment 8 is a cylinder 14 whose outer end receives a threaded plug 15. A stuffing box 15a extends through this front wall of the chamber 8 and projects into the cylinder 14. The stuffing box 15a is located in longitudinal alinement with the plug 15.

and slidably mounted in the stuffing box is a plunger 17. As shown in Fig. 2 the inner end of the plunger 17 projects into the chamber 8 while its outer end extends into the cylinder 14 and is provided with a head or stop 18, the latter serving to limit the movement of the plunger in an inward direction.

In order to prevent a too rapid conduction of heat, the inner end of the plunger 17 projecting beyond the stuffing box or bushing 15a is preferably made of bakelite or similar non-conductor, and that portion of the bushing within the chamber 8 is also preferably made of a non-conductor.

Attached centrally to the head 18 and extending longitudinally through the cylinder 14 is a rod 19 whose forward end passes through the plug 15. To normally urge the plunger and rod 19 in an inward longitudinal direction an expansible coil spring 20 encircles this rod 19 and has one end positioned against the plug 15 and its opposite end bears against a disk 21 attached to the rod in close proximity to the head 18.

A casing 22 is arranged in advance of the cylinder 14 and journaled therein is a vertically extending shaft 23a which carries a horizontally disposed gear segment 24.

Rack teeth 25 are formed on the outer end of the rod 19 and engage the gear segment 24. The lower end of the shaft 23 carries a socket 26 for the reception of a shank 27 of a rotatable valve element. The invention provides means whereby the shank 27 of the valve element may be rotated independently of the gear segment and rack teeth. To that end the shaft 23a is formed in longitudinally aligned sections 28 and 28a. Disks 30 are fixed to the opposed ends of these sections and are arranged in abutting relation. Registering arcuate slots 31 are provided in these disks and extending through these slots are bolts 32 for normally clamping the disks together for unitary rotation. The lower disk 30 is provided with a laterally extending handle 33. When it is desired to operate the socket 26 manually the nuts for the bolts 32 are loosened and the shaft sections 28 and 28a rotated by means of the handle 34.

From the description thus far given it follows that upon expansion of water contained in the compartment 8, due to freezing, the plunger 17 will be shifted longitudinally in an outward direction and rotate the shaft 23a through the instrumentality of the rack teeth 25 and gear segment 24. By reason of the socket 26 engaging the shank 27 of the valve the latter is rotated to closed position. It will be seen that the plunger will be held against returning to normal position by reason of the ice formation in the compartment 8.

An electrical heating element 34 is supported within the compartment 8 and is adapted to melt the ice formation therein to permit

the plunger and associated parts to return to normal position. The heating element 34 has one of its terminals electrically connected with a binding post 35 mounted upon the inner end of the cylinder 14. A second binding post 36 is mounted in the cylinder 14 in longitudinal alignment with the binding post 35 and connected with the former is an electrical conductor 37. A second electrical conductor 38 is connected with the other terminal of the heating element. Both binding posts pass through insulating bushings 39 which in turn pass through a sheet of insulating material 40 mounted upon the interior of the cylinder 14.

To automatically complete an electric circuit through the binding post when the plunger 17 is in actuated position a resilient contact 41 is attached to the lower end of one of the terminals 39 and normally springs against the other binding post. In practice the conductors 37 and 38 will be connected with a suitable electric circuit including a conventional switch so that when it is desired to melt the ice to permit the device to return to normal position it is only necessary to permit electrical energy to pass through the heating element.

Normally the contact 41 is held out of engagement with the contact 36 by means of a forwardly extending pin 42 attached to the head or stop 18. As disclosed in Fig. 2 the normal position of the stop 18 is against one end of the packing gland 16 and when in that position it depresses the free end of the resilient contact. It will be apparent that when the ice in the compartment 8 has been melted the expansible spring 20 will then become operative to move the rod 19 and plunger 17 in an inward longitudinal direction to rotate the shaft 23 in a direction to open the valve.

What is claimed is:

1. In an anti-freezing apparatus, a rotatable shaft adapted to be connected with a valve, a chamber adapted to contain liquid, a spring pressed plunger having one end received in the chamber and its opposite end operatively connected with the shaft so that upon expansion of the liquid in the chamber due to formation of ice therein the shaft will be rotated in a direction to operate the valve.

2. In an anti-freezing apparatus, a rotatable shaft adapted to be connected with a valve, a chamber adapted to contain liquid, a spring pressed plunger having one end received in the chamber and its opposite end operatively connected with the shaft so that upon expansion of the liquid in the chamber due to formation of ice therein the shaft will be rotated in a direction to operate the valve, and means for heating the chamber to melt the ice and permit the plunger to return to normal position.

3. In an anti-freezing apparatus, a cham-

ber adapted to contain water, a plunger slidably mounted therein and movable in one direction by expansion of the liquid due to formation of ice in said chamber, a rotatable 5 valve shaft arranged at right angles to the plunger, and gearing between the plunger and shaft for rotating the latter incident to the longitudinal movement of the plunger.

reservoir having upper and lower chambers, the upper chamber having divergent side walls to obviate bursting due to expansion of liquid in the receptacle, a conduit establishing communication between the two chambers 70 and having a restricted passageway for forming an ice seal, and a longitudinally slideable plunger in the lower compartment and responsive to expansion of liquid occurring in the lower chamber, and a valve stem designed to operate a valve upon such movement of the plunger.

4. In combination a valve operating shaft, 10 a chamber adapted to contain liquid, a plunger slidably mounted in said chamber and movable in one direction by expansion of liquid occurring therein, means operatively connecting the valve operating shaft and plunger to move the former to valve opening and closing position incident to the movement of the plunger, a heating element associated with said chamber, means for interrupting an electrical circuit which includes 20 the heating element when the plunger is in normal position and automatically operable to complete such circuit after the plunger has been actuated.

5. In an anti-freezing apparatus, a rotatable valve shaft, a gear segment fixed thereto, a rod arranged at right angles to the shaft and having rack teeth engaging the segment, a spring pressed plunger attached to the rod, a liquid reservoir into which one end of the 30 plunger extends so that upon freezing of the liquid therein the plunger will be forced against the tension of the spring in such manner as to operate the valve.

6. In an anti-freezing apparatus, a rotatable valve shaft, a gear segment fixed thereto, a rod arranged at right angles to the shaft and having rack teeth engaging the segment, a spring pressed plunger attached to the rod, a liquid reservoir into which one end of the 40 plunger extends so that upon freezing of the liquid therein the plunger will be forced against the tension of the spring in a direction to rotate the shaft to valve closing position, and means for melting the ice in the 45 reservoir at will to permit the plunger to return to normal position.

7. In an anti-freezing apparatus, a liquid reservoir, a longitudinally movable plunger having one end received in the reservoir and 50 movable in one longitudinal direction by expansion of liquid in said chamber, a valve stem operated by such movement of the plunger, an electrical heating element in the chamber, a pair of spaced insulated contacts 55 supported above the plunger, one of which being electrically connected with the heating element, a resilient contact fixed to one of the spaced contacts and resiliently engaging the other when the plunger is in actuated 60 position, and an element carried by the plunger and disposed in the path of movement of the resilient contact to hold the same in inoperative position when the plunger is in normal position.

8. In an anti-freezing apparatus, a liquid
